CLAIM

The ornamental design for a V-twin air compressor, as shown and described.

DESCRIPTION

FIG. 1 is a perspective view of a V-twin air compressor;

FIG. 2 is a front view thereof;

FIG. 3 is a right side view thereof;

FIG. 4 is a rear view thereof;

FIG. 5 is left side view thereof; and,

FIG. 6 is a top view thereof.

The phantom lines are for illustrative purposes only and do not form part of the claimed design.
